[57]**CLAIM**

The ornamental design for a pocket tool with a translucent scale, as shown and described.

DESCRIPTION

FIG. 1 is a top perspective view of a pocket tool with a translucent scale showing our new design;

FIG. 2 is a left end view thereof;

FIG. 3 is a top plan view thereof;

FIG. 4 is a rear elevational view thereof;

FIG. 5 is a bottom plan view thereof;

FIG. 6 is a front elevational view thereof; and,

FIG. 7 is a right end view thereof.

The broken line showings of bits in various views are for illustrative purposes only and form no part of the claimed design.
